Primary Examiner — Michael A. Pratt*Assistant Examiner* — Wendy L Arminio(74) *Attorney, Agent, or Firm* — Fish IP Law, LLP(57) **CLAIM**

The ornamental design for a jar lid, as shown and described.

DESCRIPTION

FIG. 1 is a perspective view of a jar lid, shown in a position of use on a jar drawn in broken lines.

FIG. 2 is a top view of the jar lid of FIG. 1, shown removed from the jar.

FIG. 3 is a side view thereof; and,

FIG. 4 is a front view thereof.

The broken lines depict environment and form no part of the claimed design.

1 Claim, 1 Drawing Sheet(56)
